A. E. BERDON

PRESSURE FUEL FEED SYSTEM FOR HYDROCARBON ENGINES

Filed March 26, 1924

UNITED STATES PATENT OFFICE.

ALBERT E. BERDON, OF SOUTH ORANGE, NEW JERSEY, ASSIGNOR TO SELF-FEEDING VAPORIZER CORPORATION, OF NEW YORK, N. Y., A CORPORATION OF NEW YORK.

PRESSURE FUEL-FEED SYSTEM FOR HYDROCARBON ENGINES.

Application filed March 26, 1924. Serial No. 702,002.

This invention relates broadly to fuel feeding systems for hydrocarbon engines, and more especially to a pressure feed system adapted for hydrocarbon engines of the 5 automobile, the aeroplane, and similar type engines and the like.

Heretofore in the art pumps have been utilized to feed liquid fuel to hydrocarbon engines and a well known system has been 10 to use a pump to serve a small tank provided with an overflow back to the main tank and adapted to feed the carburetor by gravity feed. In this old type of system the overflow pipe is objectionable, more 15 especially in connection with automobile engines, and this system has therefore not been generally used in automobile structures, although it is in quite common use with stationary engines. This system however possesses the advantage of having a large supply tank located below the level of the carburetor and a very small supply tank above the level of the carburetor, which small tank is continually replenished by the operation 20 of the pump. The organization minimizes the fire hazard due to the fact that only a small supply of fuel is maintained near the engine and above the carburetor and provides a substantially constant head pressure to feed the carburetor. Pressure supply systems are common in the art in which air pressure is pumped to the main supply tank to provide a pressure over the fuel in the main supply tank and thereby force the fuel to the carburetor. This system insures an adequate supply of fuel to the carburetor, but possesses the disadvantage of fire hazard in that if any leakage occurs in the carburetor float control valve whereby the carburetor is flooded the fuel will leak out and run on the floor beneath the car and create a dangerous situation. Furthermore the pressure is variable, and since the main tank must withstand the pressure it must be extra strong which adds to the cost. 45

The present invention overcomes the difficulties of the known art and at the same time carries forward the advantages of the known art by providing a novel pumping apparatus which constantly maintains a

small supply of fuel to feed the carburetor and which supply is under a predetermined pressure and is furnished according to the needs of the carburetor. Broadly, the present invention comprises constructions in 55 which a small supply of fuel is under a predetermined pressure and is replenished as it is used by the carburetor, with the replenishing operation taking place through mechanism positively operated mechanically 60 by a moving part of the engine. In a simple form it may comprise a pumping mechanism which is operated by a moving part of the engine, for example, a valve rod, and which is so constructed that fuel is 65 continually fed to the carburetor conduit by the pump until a predetermined pressure is reached in the said conduit leading from the pump to the carburetor, at which time the pump ceases to function. The functioning 70 of the pump is proportionate to the reduction in pressure from the predetermined pressure so that a small reduction in pressure will permit a proportional pumping operation, thereby maintaining the pressure 75 in the line to the carburetor substantially constant within relatively narrow limits in which the maximum pressure is substantially a predetermined fixed limit.

Having generally set forth the aspects of 80 the invention, it may be stated that the principal object is a fuel feed system for a hydrocarbon engine in which liquid fuel is raised from a main supply, preferably located at a low level, by mechanically operated mechanism which delivers the said fuel to the carburetor under substantially constant pressure. 85

Another object of the invention is to provide a system of the character specified in 90 which the maximum pressure on the delivered fuel may be predetermined.

A further object of the present invention is a system of the character specified in 95 which a predetermined pressure may be established at which the mechanical driven element of the system ceases to operate.

A still further object of the present invention is a system in which provision is made to prevent the back flow of the fuel 100

from the pressure line when the mechanically operated pump ceases to operate.

A still further object of the present invention is a system of the character specified 5 in which constructions are provided to prevent an overflow of liquid fuel from the main supply tank to the carburetor when the main supply tank is raised above the carburetor, as occurs in an automobile on a 10 steep grade with the engine down hill.

Another and important object of the present invention is a system substantially as specified in which the delivery of liquid fuel to the carburetor is dependent upon the 15 needs of the carburetor regardless of the speed of operation of the moving part which operates the pump of the system.

Other and further objects of the present invention will in part be obvious and will 20 in part be pointed out hereinafter in the specification following by reference to the accompanying drawings forming a part of this application.

Realizing that the present invention may 25 be embodied in constructions other than those herein specifically shown and described, it is desired that the disclosure here-with shall be considered as illustrative and not in the limiting sense.

30 Throughout the drawings like parts are indicated by like characters, and

Figure 1 is a diagrammatic view illustrating the invention as applied to a hydro-carbon engine of the automobile type;

35 Figure 2 is a sectional view through one form of pumping apparatus adapted for use in connection with the present invention;

Figure 3 is an elevational view of the device shown in Figure 1; and

40 Figure 4 is a plan view of the device shown in Figures 2 and 3.

Referring now more especially to Figure 1, which diagrammatically illustrates the whole system a main tank 1 open to atmosphere is connected by a suitable conduit 2 to a mechanical pump 4, which is operated by some moving part of a hydrocarbon engine 5, for example, one of the valve rods 6. This pump 4 is connected by a suitable 45 conduit 7 to a carburetor 8 in such manner that as the valve rod 6 reciprocates in its operation it will operate an actuating lever 9 of the pump 4 and thereby actuate the pump to draw gasoline from the main tank 50 1 to deliver said fuel to the carburetor 8 under a constant predetermined pressure, as will now be explained by reference to a more detailed description of the mechanical pumping apparatus. Upon reference to Figures 55 2 to 4 inclusive, which illustrate the preferred form of mechanical pump, it will be observed that a diaphragm pump has been chosen in order to avoid sliding packed joints in the fuel line. Other types of 60 pumping apparatus may be utilized without

departing from the invention, but the diaphragm type of pump is preferred. Referring to the details of the pump illustrated, it will be noted that a body portion 10 is constructed to carry the operating valves and is provided on the inlet side with an inlet connection 11 which is arranged on its inner end with a valve seat against which an inlet valve 12 is normally seated by means of a light spring 14. The body portion 10 is cut away, preferably, around the valve 12 and inlet connection to provide a space 15 in which the valve 12 may operate and also to provide a liquid seal which tends to obviate air pockets. This space 15 leads by 70 means of a conduit 16 to a pumping recess 17 in the upper part of the body portion, which pumping recess at the opposite side of the body portion leads to an outlet collar 18 that is provided with a seat against which an outlet valve 19 is normally seated by a light spring 20. This outlet valve 20 and the end of the outlet collar 18 which is provided with a valve seat, are also surrounded with an annular space 21, allowing 75 clearance for the valve operation, and likewise providing a liquid seal for the valve. This outlet space 21 communicates with an outlet conduit 22 that connects with the conduit 7 leading from the carburetor. The 80 body portion 10 of the pump is adapted to carry a cover portion 24 which may be attached to the body portion by machine screws 25 or the like, and this cover portion 24 is also provided with a recess 26 opposite 85 to the pumping recess 17 in the body portion 10. A diaphragm 27 of the ordinary type, preferably corrugated, is mounted between the body portion 10 and the cover portion 24 and is adapted to be flexed back and forth in the spaces formed by the recesses 90 17 and 26 to provide the pumping action. An operating stem 28 is operatively connected with the diaphragm 27 as by means of suitable washers 29 and 30 and is adapted 95 to be guided at its free end by an adjustable guide or collar 31 which preferably is screw threaded in an extension 32 on the cover 100 24. A spring 34 surrounds the operating stem 28 and is compressed between the adjustable guide 31 and the washer 29. The guide 31 is adjustable in the extension 32 in order to predetermine the amount of compression of the spring 34 for the purpose 105 hereinabove described. The upper end of the stem 28 is connected by an extensible spring 35 with the actuating lever 9 which is pivoted at 36 to a bracket 37 that is mounted 110 on the cover portion 24. The pump is mounted relatively to the engine so that the other end of this actuating lever 9 is in operative relation to the valve rod 6 as previously stated, and this operative relation preferably comprises a bifurcated end 38 on the lever 9 extending around the valve rod 6 115 120 125 130

and above an adjustable collar 39 on the valve rod 6 so that the lever 9 is raised by the collar 39 as the valve rod 6 moves upwardly, but is lowered by the action of the 5 compression spring 34 which is carried by the operating stem 28, as the valve rod 6 is lowered.

In the operation of the device, it will be observed that as the engine turns over and 10 the valve rod 6 is reciprocated, the adjustable collar 39 on the valve rod 6 will contact with and will raise the outer end of the actuating lever 9 so that it acts as a lever of the second class to pull on the extensible 15 spring 35. The pull of the spring 35 is communicated to the operating stem 38 and thereby tends to raise the stem and compress the compression spring 34. This causes the diaphragm 27 to be flexed upwardly and 20 produce a partial vacuum whereby atmospheric pressure in the main tank, which is open to atmosphere, causes liquid fuel to flow through the conduit 2 past the inlet valve 12 and into the pumping space 17 in 25 the body portion beneath the upwardly flexed diaphragm 27. As the valve rod 6 lowers on its return stroke, the adjustable collar 39 is lowered away from the outer end of the lever 9 so that the pull on the extension 30 spring 35 is relieved and the full force of the compression spring 34 now acts on the diaphragm to produce pressure on the fuel beneath the diaphragm in the space 17. This action assists the light spring 14 in closing 35 the inlet valve 12 and also overcomes the pressure of the light spring 20 to open the outlet valve 19, thereby driving the fuel from the recess 17 into the conduit 7 leading to the carburetor. This action continues as 40 the engine continues to turn over until a sufficient amount of liquid is supplied to the carburetor to cause the carburetor float in the float chamber to close the carburetor inlet valve thereby closing the conduit from the 45 pump to the carburetor, stopping the flow of fuel to the carburetor. As the engine continues to run the valve rod 6 will again, through the collar 39, raise the operating arm 9, which again in turn will flex the dia- 50 phragm 27 in an upward direction and on the return stroke the compression spring 34 will again tend to force the diaphragm downward. Now that the fuel line leading to the carburetor is substantially closed and is filled 55 with liquid fuel, this fuel in the closed conduit tends to resist the return of the dia- phragm to normal. The diaphragm will therefore stand stationary. As soon, however, as a small amount of gasoline is 60 released from the conduit into the float chamber of the carburetor by the float valve, the diaphragm under the influence of the spring 34 will lower proportionately and on the next upstroke of the valve 65 rod 6 the fuel necessary to fill the void

caused by the fuel that was used, will be raised into the pump chamber 17, so that the diaphragm is again held up and the liquid on the outlet side of the pump, in the conduits leading to the carburetor, will again be under 70 the pressure produced by the action of the compression spring 34 on the diaphragm 27. In view of the fact that the static pressure on the compression spring 34 may be predetermined by adjusting the guide collar 31, it 75 follows that during the operation of the engine the fuel on the outlet side of the pump, namely, that in the conduit line leading to the carburetor, is maintained substantially under a predetermined pressure. It 80 will be understood that the extension spring 35 is of such strength as to overcome the maximum compression which may be applied to the compression spring 34. After the feed line to the carburetor has become 85 filled with gasoline and momentarily there is no fuel feeding into the float chamber of the carburetor and while the diaphragm 27 is being maintained substantially stationary, and movement in an upward direction by the 90 outer end of the lever 9 is allowed by the extension of the extension spring 35, so there is always an excess of motion to insure prompt action of the diaphragm. This action 95 will occur when the washer 29 on the operating stem 28 contacts with the stop 40 on the cover 24, which stop fixes the upper limit of movement of the diaphragm. Movement of the diaphragm is limited by the contacting of the end 41 of the operating stem 28 with the bottom of the recess 17, which comprises a lower limit stop for the diaphragm and consequently relieves the diaphragm of abnormal downward stress action 100 of the spring 34, when the pumping chamber 17 is empty.

It will be observed that the inlet valve 12 acts to hold the pressure established in the feed line conduit leading to the carburetor, as well or to perform its normal pumping function; and that while the outlet valve 19 performs its normal pumping function it also operates to prevent an overflow from the main tank where the main tank is elevated, but in practice the pump is usually located 110 at a point so high that the main tank is not likely to be raised above it and the outlet valve effectually blocks any siphoning action that might tend to occur where the main tank is elevated above the carburetor. 115

From the foregoing it will be observed that the present system comprises an arrangement of parts whereby a relatively small amount of liquid fuel is maintained under a predetermined pressure by positively mechanically operated constructions, which automatically functions to supply the carburetor according to its requirements. 125

Having thus described my invention what I claim is: 130

In combination, a fuel supply source and a fuel receiving element, a pumping mechanism disposed between the two comprising a chamber having a diaphragm therein, a rod secured to said diaphragm, a spring connected to said rod and an operating mechanism secured to said spring for flexing said diaphragm in one direction, a spring dis-

posed around said rod and having fixed bearings at either end thereof, whereby when said latter spring is compressed it may flex said diaphragm in the opposite direction and inlet and outlet passages connecting said chamber with said fuel supply source and said fuel receiving element. 10

ALBERT E. BERDON.
